[57] CLAIM

The ornamental design for a car telephone set, as shown and described.

DESCRIPTION

FIG. 1 is a front elevation of a car telephone set showing our new design;

FIG. 2 is a rear elevation thereof;

FIG. 3 is a left side elevation thereof;

FIG. 4 is a right side elevation thereof;

FIG. 6 is a bottom plan view thereof;

FIG. 7 is a side perspective view thereof;

FIG. 8 is a perspective view taken in an alternate position from FIG. 7;

FIG. 9 is a side perspective view with the handset removed from the telephone base; and

FIG. 10 is a top perspective view of the telephone set mounted on a vehicle console.

The broken lines are shown for illustrative purposes only.
